UNITED STATES PATENT OFFICE.

OTTO BECKER, JR., OF BARMEN, GERMANY.

ELECTRIC SAFETY LAMP FOR MINERS.

Application filed April 28, 1927, Serial No. 187,202, and in Germany November 4, 1925.

The invention relates to an electric safety lamp for miners having a current generator coupled to a compressed air motor arranged in a casing in which the electric incandescent lamp is carried, a protecting hood which encloses the lamp and is under pressure when the lamp is in operation together with a switch for breaking the circuit of the incandescent lamp which is held in the closed position owing to the pressure existing in the protecting hood. The lamp which forms the subject matter of the present invention differs from the known miners' lamps of this kind in which the protecting hood consists of a glass globe, in the first place, in that the protecting hood for the incandescent lamp is formed by a metal case, which is advantageously made in one piece with the casing in which the lamp is carried, and a glass front which is removably fitted thereto. By this means it is possible, on the one hand, to make the wall of the protecting hood thinner and lighter than heretofore. On the other hand only the glass front is exposed to the danger of breakage or damage by splinters of stone. It can, however, in contra-distinction to the complete glass globes hitherto employed, be effectively protected by means of wire netting or the like fastened to a forwardly projecting edge of the metal case so that damage cannot occur so easily. Further, the disadvantage, which exists in the previously known lamps of this kind, namely that if a crack in the glass occurs the entire protecting hood can be caused to burst owing to the pressure existing within it whereby people are easily endangered by flying pieces of glass, is avoided. The new lamp, on the other hand, can be used, even when the glass front of the protecting hood is cracked, so long as the lack of air-tightness is not so great that, owing to the escape of air, the fall in pressure which occurs in the protecting hood is so great as to cause the disconnection of the circuit of the incandescent lamp. At the same time the air escaping through the places which are not air-tight prevents the access of any outer air, which may be explosive, owing to its being mixed with fire-damp or coal-dust.

Finally, a special advantage which results from constructing the protecting hood from a metal case and a glass front is that, it is then possible to conduct the compressed air which escapes when the glass front is dam-

aged or broken in such a manner that the outer air cannot reach the filament of the incandescent lamp, which is generally also broken when the glass front is broken, before the circuit breaking switch has switched it off. This can be effected, in accordance with the invention, by arranging the reflector of the incandescent lamp so as to cut off the rear portion of the space within the protecting hood containing the inlet opening for the compressed air from the front portion of the hood containing the lamp in such a manner that the two spaces are only in connection the one with the other by means of an annular gap which is approximately concentric with the lamp. The result of this arrangement is that, when the glass front is damaged or broken, the air can only escape in a stream of annular cross-section which envelops the lamp, whereby the incandescent lamp is screened from the outer air.

In order to maintain the pressure acting on the walls of the protecting hood as small as possible and consequently to be able to make the hood as light as possible, the controlling pressure in the hood is advantageously obtained not, as in some known types of miners' lamps, by conducting fresh compressed air into the hood, but, in a manner also known per se, by conducting the exhaust air from the motor into the hood and at the same time throttling down the exhaust air at its outlet into the atmosphere. Whereas, in the known lamps having an arrangement of this nature, the exhaust air from the motor flows into the atmosphere at the rear end of the casing and the hood is only connected with the casing of the motor in such a manner that the pressure of the throttled exhaust air is transmitted to the hood, in the lamp in accordance with the invention the exhaust air from the motor, and preferably the whole of the exhaust air, is conducted right through the protecting hood which is provided with an outlet opening leading into the atmosphere. This ensures that, if the compressed air escapes owing to a crack occurring in the glass front or owing to lack of air-tightness produced by other causes, sufficient exhaust air always flows through the hood either to maintain a high enough pressure in the hood for holding the switch closed, or when the glass front has been much damaged or broken, to maintain a screen of compressed air which protects

the lamp from the access of outer air until it has been completely extinguished.

With the above described arrangement, in which the exhaust air from the motor 5 which drives the current generator is conducted right through the protecting hood of the lamp and is throttled down at its outlet into the atmosphere, it is possible also, on the one hand, to operate with a low excess 10 of pressure in the protecting hood and, on the other hand, to construct the switch for breaking the circuit of the lamp or the device for closing this switch in such a manner that, in spite of the low pressure in the hood, the pressure is sufficiently high to 15 press the contacts of the switch together so that a good connection is made, while the device can also be made so sensitive that the switch is opened even when a relatively 20 small fall of pressure occurs in the protecting hood. This result is obtained, in accordance with the invention, by throttling the exhaust air which flows into the atmosphere by means of a movable throttling disc which is 25 connected with the switch for breaking the circuit in such a manner that the switch is held closed against the action of an opening spring by means of the pressure exerted by the exhaust air on the throttling disc.

30 A constructional embodiment of the invention is illustrated by way of example in the accompanying drawing, which shows a longitudinal sectional view of a miner's lamp arranged in accordance with the invention.

In the drawing, 1 is a cylindrical metal casing having a fixed wall 2 in front and a removable wall 3 at the back. The rear side of the fixed front wall 2 is provided with a 40 tube-like extension 4, the interior of which is divided into two parts by means of a fixed intermediate wall 4^a. The front portion of the tubular extension 4 serves for the reception of the socket 27^a of an incandescent 45 electric lamp 27, the glass bulb of which containing the filament is in front of the fixed front wall 2. The incandescent lamp 27 is surrounded by a metal case 5 of more or less hopper-like shape which is arranged 50 at the front end of the casing 1 and forms, together with a glass disc 17, a protecting hood for the lamp. The casing 1, front wall 2, tubular extension 4 and case 5 are preferably cast in one piece as shown in the drawing. The glass disc 17 which closes the case 5 is secured by means of an internally threaded ring 19, which presses the disc against the edge of the case 5, a packing ring 18 being interposed between the two. A 55 wire net 21, which is fixed to the threaded ring 19, can be arranged in front of the glass disc 17 in order to protect it from possible damage. The rear removable wall 3 of the casing is of hood-like shape and the 60 space within it is shut off from the interior

of the casing 1 by means of an intermediate wall 12, which is removably held between the casing 1 and the removable rear wall 3.

The casing 1 contains a current generator which, in order to avoid sliding contacts, 70 consists of several fixed coils 6 and a rotor 7 formed by a permanent magnet. The latter is mounted on a shaft 8 which is journaled on one side in the rear portion of the tubular extension 4 of the front wall 2 and on the other side in a hub-like extension 12^a in the intermediate wall 12. The rear end of the shaft 8 projects into the space within the hood-like rear wall 3 and carries a turbine wheel 11 which serves the purpose of driving 80 the current generator. The compressed air for driving the turbine wheel 11 is admitted through an inlet 13, which is cast in the wall of the casing and is in connection with a passage 14 which opens onto the blades of 85 the turbine wheel 11.

The exhaust air passes, through an opening 15 provided at the edge of the intermediate wall 12 and a longitudinal channel 16 in the casing 1 connected therewith, into the protecting hood 5 of the lamp 27. From here the air escapes through a special outlet into the atmosphere, being throttled in such a manner that an excess of pressure above the atmospheric pressure exists within the 95 protecting hood 5. This outlet is arranged in the following manner:

The side of the front wall 2 of the casing which is away from the mouth of the channel 16 contains a recess 45, 45^a in the form of a bore of which the rear portion is reduced and of which the front wider portion 45^a contains a box-like chamber 46 which is held in place by a cover 47 which is screwed into an internal thread provided in the recess 45^a. The cover 47 has several openings 48 through which the exhaust air can escape from the hood 5 into the chamber 46. That part of the wall of the chamber 46 which is adjacent to the rear end of the chamber contains on the other hand one or more outlet openings 50, which are in connection with the actual exhaust opening 52 leading to the atmosphere by means of an annular channel 51 surrounding the 110 chamber 46. The exhaust opening 52 is preferably covered, as illustrated, by means of gauze 53 for protection against the ingress of dirt. Further, there is also arranged in front of it a guard plate 54 which overlaps the opening, one or more side outlet passages for the air being provided, and prevents the exhaust opening 52 being closed by the hand whereby the operation 115 of the lamp would be interfered with.

A throttling disc 70, the diameter of which is somewhat less than the clear width of the chamber 46, is arranged in the box-like chamber 46 between the cover 47 and the side air outlet openings 50, so that a narrow 120

annular space is left around the blocking disc through which space the exhaust air from the hood 5 must flow in order to escape through the chamber 46, opening 50, 6 annular channel 51 and the exhaust outlet 52 into the atmosphere. The throttling disc 70 is fitted on a rod 71, which is tightly guided in a stuffing-box 55 cast in the rear end of the chamber 46, and is movable together with this rod like a piston in the chamber 46. A spring 56 which surrounds the stuffing-box 55 and the rod 71 always tends to press the rod 71 together with the disc 70 into the forward end position illustrated in the drawing.

The disc 70 serves the purpose, on the one hand, of throttling the escaping air and, on the other hand, of controlling a circuit breaking switch which is arranged in the rear narrower portion 45 of the recess 45, 45^a. This switch consists of two fixed contacts 57, 58 arranged at the bottom of the recess and a contact bridge 59, for connecting the two. The rear ends of 25 these two contacts are formed as terminals and one of them, namely 57, is connected by a conductor 60 with the current generator. The other contact 58 is in connection through a conductor 61 with one of the contacts in the base of the incandescent lamp 27, the second contact of which is connected by a conductor 62, a third terminal 63 and a conductor 62^a again with the current generator. The contact bridge 59 is fixed to 30 and insulated from the forked end 71^a of the rod 71 of the disc 70 which rod passes through the bottom of the chamber 46 into the rear portion 45 of the recess 45, 45^a. The said contact bridge can at the same 35 time swing about an axis 64 at right angles to the rod 71, so that it can adjust itself automatically to the fixed contacts 57, 58, when pressed against them, in such a manner that it makes contact over the full extent of the contact surfaces of the fixed contacts. This bridge 59 contains a preliminary contact which consists of a U-shaped member or bow 65, which is made of precious metal, for example, silver or platinum, and of which the two limbs are guided in the end portions of the bridge, and which is pressed forwards by means of a spring 66 arranged between the forked head of the rod 71 and the limbs of the bow. 40 This spring simultaneously serves the purpose of normally holding the contact bridge 59 to the middle position illustrated. On closing the switch, which is effected by the pressure of the exhaust air on the disc 70, 45 the fixed contacts 57, 58 are first connected together by the preliminary contact 65 and only when the circuit has thus been closed does the bridge itself come to rest against the contacts. Conversely, when the switch 50 is opened by the spring 56, the bridge 59

first moves away from the contacts 57, 58, after which the preliminary contact 65 breaks the circuit, so that by this means over-heating of the contacts is prevented. The rear portion 45 of the recess 45, 45^a 70 containing the circuit breaking switch is completely enclosed by the bottom of the chamber 46 which is pressed by means of the cover 47 against the shoulder 67 of the recess. This portion 45 is completely closed and contains no opening except that for the passage of the rod 71, so that any spark which may occur on operating the switch remains enclosed in the chamber in which the switch is contained.

The protecting hood 5 of the incandescent lamp 27 contains a reflector 39, 39^a, which, as may be seen from the drawing, is transversely divided into two parts. Its rear or inner portion 39 is fixed to the fixed front wall of the casing 2 while the front or outer portion 39^a is held by clamping a collar or flanged edge with which it is provided together with the glass disc 17 and the packing ring 18 between the casing of the hood 5 and the threaded ring 19. Between the two parts 39, 39^a of the reflector there is left an annular gap 42 which is concentric with the incandescent lamp 27 and forms the only connection between the two spaces within the hood 5 which lie in front of and behind the reflector respectively. If the glass disc 17 is broken or damaged, the forwardly escaping exhaust air from the turbine is then compelled to flow through the annular gap 42. In doing so it forms a current of air of annular cross-section which envelops the lamp 27 and thus prevents the outer air, which may in some cases be explosive, from reaching the filament of the lamp, which 95 may possibly also be broken, and being thereby ignited. Before the pressure in the lamp has become so low that the protecting screen of air around the lamp disappears, the lamp circuit is broken by the switch 57, 58, 59 which opens when the pressure in the hood 5 falls and the filament is thereby extinguished.

The method of operation of the new lamp is as follows:

On opening a cock in the compressed air inlet conduit, compressed air is admitted to the turbine 11 and the turbine then drives the dynamo 6, 7. The exhaust air from the turbine flows through the channels 15, 16 120 into the protecting hood 5 of the incandescent lamp 27 and thence through the chamber 46, annular channel 51 and the exhaust opening 52 into the atmosphere. The air must on its way pass through the narrow annular space between the throttling disc 70 and the wall of the passage formed by the chamber 46 whereby it is throttled down to such an extent that an excess of pressure is produced in the hood 5 which is sufficient to 125 130

form at the annular gap 42 in the reflector 39, 39^a, a screen of air which protects the incandescent lamp 27 if the glass disc 17 is damaged. Owing to the throttling of the 5 exhaust air at the disc 70, the air exerts so great a pressure on this disc in the opposite direction to the pressure of a spring 56 that the disc 70 is pushed inwards. The contact bridge 59 on the rod 71 is thereby pressed 10 against the fixed contacts 57, 58 and the circuit of the current generator and the incandescent lamp is thus closed. The incandescent lamp now lights up as long as an excess of pressure exists in the protecting hood 15 5. If the glass wall 17 of the hood 5 is broken or damaged, it then becomes possible for the exhaust air to take another course, namely it flows through the annular space 42 and the opening produced by the breakage of the 20 glass disc 17. The annular space 42 then gives the current of air which is flowing out forwardly an annular cross-section which envelops the lamp 27, so that the outer air cannot gain access to the filament of the 25 incandescent lamp which may also have been destroyed. Owing to the air streaming out through the annular space 42 the pressure within the protecting hood 5 is reduced. The pressure of the exhaust air on the throttling disc 70 also ceases and the switch 57, 30 58, 59 is opened by the spring 56. The circuit is thereby broken and the filament of the lamp extinguished. The extinguishing of the filament occurs in every case while 35 the filament is still enveloped by the annular current streaming out through the gap 42, whereby the ignition of the outer air, which may be explosive, by the filament of the incandescent lamp is prevented with certainty. A similar action takes place if the 40 destruction of the glass wall 17 of the protecting hood 5 takes place immediately after the turbine has been disconnected, that is to say, when the lamp 27 is still supplied with some current from the dynamo, owing to its 45 not stopping immediately, and so still lights up weakly. So long as the circuit is not broken by the switch 57, 58, 59 sufficient pressure exists in the protecting hood 5 to 50 form at the annular space 42 a screen of exhaust air which protects the incandescent lamp from the access of the outer air. Long before this screening of the incandescent lamp ceases the circuit is broken by the circuit-breaking switch and the filament of the 55 lamp extinguished.

As may be seen, owing to the arrangement of the throttling disc 70 which controls the circuit breaking switch 57, 58, 59, 60 it is possible to operate with a relatively low excess of pressure in the hood 5 whereby, on the one hand, the efficiency of the compressed air motor 11 is increased, and, on the other hand, the danger of the parts 65 of the damaged glass disc 17 being blown

out is considerably reduced. At the same time, however, owing to the construction of the controlling member for the switch as a throttling disc for the emerging exhaust air, on the one hand, a relatively high pressure 70 is exerted upon the throttling disc 70 when the glass disc is undamaged so that the bridge piece 59 and the contacts 57, 58 are firmly pressed together while, on the other hand, the controlling member for the switch is highly sensitive so that the switch is opened even when a relatively small fall in pressure occurs in the hood 5. This ensures with the highest degree of certainty 75 that the lamp is extinguished before the 80 screen of air which protects it disappears.

The invention is of course, not limited to the particular example illustrated but many alterations and other forms of construction are possible within the scope of 85 the appended claims, without departing from the spirit or sacrificing any of the advantages of the invention.

I claim:

1. A safety electric lamp comprising a 90 casing having separate motor, generator and lamp chambers, an air inlet to the motor chamber, an air conducting passage between the motor and lamp chambers and a lateral final air outlet in rear of the lamp chamber, a turbine in the motor chamber, a current generator in the generator chamber driven by said motor, a lamp in the lamp chamber supplied with current from the generator, a lens closing the front of the lamp chamber, a reflector partition subdividing the lamp chamber into front and rear compartments, with which rear compartment the air passage communicates, 95 said partition being provided with an air gap connecting the two compartments and surrounding the lamp, a throttling device arranged in the line of flow of the air from the rear compartment to the final air outlet, 100 and a switch device controlling the supply of current to the lamp and governed in action by said throttling device.

2. A safety electric lamp comprising a 115 casing having a rear motor compartment provided with an air inlet, a front lamp compartment provided with a lens at the front thereof, an intermediate generator compartment, an air flow passage between the motor compartment and the lamp chamber, and a final exhaust outlet at one side of the casing and in rear of the lamp chamber, a turbine motor in the motor compartment, an electric generator in the generator compartment, a lamp in the lamp compartment and supplied with current from said generator, a reflector partition subdividing the lamp compartment into front and rear chambers with which rear chamber the air 120 passage communicates, said partition being provided with an annular air gap connect- 125 130

- ing said chambers and surrounding the lamp, a throttling disk arranged in the line of flow of the air from said rear chamber to the final exhaust outlet, a spring resisting 5 movement of said disk in the throttling direction, and a circuit make and break switch governed by said disk and controlling the flow of current from the generator to the lamp.
- 10 3. In an electrical safety lamp, a casing having a lamp chamber and an air exhaust outlet in communication with the rear portion of the lamp chamber, a glass wall closing the front of the lamp chamber, a generator in the casing, an incandescent lamp in the lamp chamber and supplied with current from the generator, an air motor in the casing for driving the generator, the casing having a passage for conducting exhaust air 15 from the motor to the rear portion of the lamp casing, means controlled by pressure conditions in the lamp chamber for governing the flow of air from the lamp chamber to the air exhaust outlet and letting on or cutting off the flow of current from the generator to the lamp, and a reflector in the lamp chamber and surrounding the lamp and separating the lamp chamber into front and rear compartments, the former containing 20 the lamp bulb and the latter communicating with the exhaust outlet and the air conducting passage leading from the motor, said reflector having a restricted air passage between said compartments and about the lamp bulb and adapted for the outflow of a screening stream of air from the rear compartment to the front compartment and about the lamp bulb upon the fracture of said glass front wall of the lamp chamber. 25
5. In an electrical safety lamp, a casing having a lamp chamber and a lateral air exhaust outlet, a glass wall closing the front of the lamp chamber, a generator in the casing, an incandescent lamp in the lamp chamber 30 and supplied with current from the generator, a wall at the rear of the lamp chamber and separating the same from the part of the casing containing the generator, said wall being provided with a lamp socket receiving the base of the lamp and with a recess having an annular groove therein communicating with the exhaust outlet, an air motor in the casing for driving the generator, the casing having a passage for conducting exhaust air from the motor to the rear portion of the lamp casing, a casing fitted in said recess in the rear wall of the lamp chamber and dividing the same into compartments in front and rear of said 35 groove, the front compartment being in communication with the lamp chamber and having a lateral port communicating with the groove and air exhaust outlet, current supplying connections between the generator and lamp including contacts in the rear compartment of the recess, a switch in said rear compartment of the recess for coaction with said contacts, a throttling disk in the front compartment of the recess and controlling the flow of air from the lamp chamber through said port to the exhaust outlet, and a switch in the rear compartment of the recess governed by variations of pressure of the air upon the throttling disk for moving 40 said switch into and out of engagement with the contacts. 45
4. In an electrical safety lamp, a casing having a lamp chamber and an air exhaust outlet in communication with the rear portion of the lamp chamber, a glass wall closing the front of the lamp chamber, a generator in the casing, an incandescent lamp in the lamp chamber and supplied with current from the generator, an air motor in the casing for driving the generator, the casing having a passage for conducting exhaust air from the motor to the rear portion of the lamp casing, means controlled by pressure conditions in the lamp chamber for governing the flow of air from the lamp chamber to the air exhaust outlet and letting on or cutting off the 50 flow of current from the generator to the lamp, and a reflector in the lamp chamber and surrounding the lamp and separating the lamp chamber into front and rear compartments, the former containing the lamp bulb and the latter communicating with the exhaust outlet and the air conducting passage leading from the motor, said reflector having a restricted air passage between said compartments and about the lamp bulb and adapted for the outflow of a screening stream of air from the rear compartment to the front compartment and about the lamp bulb upon the fracture of said glass front wall of the lamp chamber. 55
- 40 4. In an electrical safety lamp, a casing having a lamp chamber and an air exhaust outlet in communication with the rear portion of the lamp chamber, a glass wall closing the front of the lamp chamber, a generator in the casing, an incandescent lamp in the lamp chamber and supplied with current from the generator, an air motor in the casing for driving the generator, the casing having a passage for conducting exhaust air from the motor to the rear portion of the lamp casing, means controlled by pressure conditions in the lamp chamber for governing the flow of air from the lamp chamber to the air exhaust outlet and letting on or cutting off the flow of current from the generator to the lamp, and a reflector in the lamp chamber and surrounding the lamp and separating the lamp chamber into front and rear compartments, the former containing the lamp bulb and the latter communicating with the exhaust outlet and the air conducting passage leading from the motor, said reflector having a restricted air passage between said compartments and about the lamp bulb and adapted for the outflow of a screening stream of air from the rear compartment to the front compartment and about the lamp bulb upon the fracture of said glass front wall of the lamp chamber. 60
